(No Model.)

M. J. HOLLAND.
FIRE EXTINGUISHER.

No. 497,180.

Patented May 9, 1893.

HIS ATTORNEY

UNITED STATES PATENT OFFICE.

MICHAEL JOSEPH HOLLAND, OF JERSEY CITY, NEW JERSEY.

FIRE-EXTINGUISHER.

SPECIFICATION forming part of Letters Patent No. 497,180, dated May 9, 1893.

Application filed January 22, 1891. Serial No. 378,723. (No model.)

To all whom it may concern:

Be it known that I, MICHAEL JOSEPH HOLLAND, of Jersey City, in the county of Hudson and State of New Jersey, have invented an 5 Improvement in Fire-Extinguishers, of which the following is a specification.

The object of my improvement is to provide for extinguishing fires more effectually than heretofore has been possible.

10 The improvement is particularly applicable to use on steamships although not confined thereto.

The improvement consists in taking the carbonic acid gas resulting from combustion and 15 directing it to the fire to be extinguished. The improvement involves various mechanical parts for this purpose.

10 The accompanying drawing is a longitudinal section of a steamship fitted with apparatus involving my improvement, a portion of the steamship being broken away to economize space.

20 A designates a system of boilers provided with furnaces discharging carbonic acid gas resulting from combustion into a smoke-stack or flue B.

25 C designates a pipe leading from the smoke-stack or flue B, and communicating with a scrubber D. From this scrubber a pipe, E, 30 extends to a pump or suction blower F, which is capable of drawing the carbonic acid gas from the stack or flue B and forcing it into any desired part of the vessel.

35 G designates a pipe leading into the lower part of the vessel. It may discharge into a chamber covered by a screen H if desired, or it may open directly into the main hull of the vessel.

40 I designates a pipe discharging into the air outside the vessel. A pipe, J, extends between the pipe E and the pipe G, and a pipe K extends between the latter and the pipe I. The blower is connected with the pipe I by means of a pipe L. The pipe E has a stop 45 cock e combined with it. A similar stop cock j is combined with the pipe J. A stop cock k is combined with a pipe K and a stop cock i is combined with the pipe I.

50 Whenever it is desired to force carbonic acid gas into the hull of the vessel, the stop cocks e k will be opened and the stop cocks i j will be closed, whereupon the pump or blower F will draw the carbonic acid gas from the stack or flue B through the pipe C,

scrubber D and pipe E, and force it thence 55 through the pipes L K into the pipe G, so that it will be discharged into the hull of the vessel.

After the extinction of a fire, it may be desirable to free the hull of the vessel from 60 the carbonic acid gas, and this may be readily done by means of the pump or blower F if the stop cocks e k are closed and the stop cocks i j are opened, for then the pump or blower will draw the gases within the hull out through 65 the pipe G, thence through the pipe J into such pump or blower and force them through the pipe L into the pipe I so as to discharge them into the air above the vessel. Obviously the pipe C could communicate with the furnace 70 instead of with the stack or flue with the same result.

It will be readily seen that the apparatus which I have described could be applied to any furnace or fire chamber or a flue leading 75 therefrom, and would serve as an effectual means for extinguishing fire.

What I claim as my invention, and desire to secure by Letters Patent, is—

1. The combination with a furnace, stack, or flue, of a scrubber, a pipe leading from the furnace, stack, or flue to the scrubber, a blower having a pipe connection with the scrubber, a cock in said pipe, a pipe leading into a vessel, a pipe communicating with the blower 85 and discharging outside the vessel, a cock in said pipe, a pipe, provided with a cock, extending from the connection between the scrubber and blower to the pipe leading into the vessel and a pipe, having a cock, leading 90 from the last named pipe into the discharge pipe, the said blower being arranged between the furnace, stack, or flue and the discharge pipe, substantially as specified.

2. In a fire extinguisher, the fan blower, a 95 valved gas supply pipe connected to one side of the blower casing, a valved force pipe leading from the other side of the blower casing, and a valved exhaust pipe also connected with the blower casing and with said force 100 pipe, substantially as set forth.

In testimony whereof I have signed my name to this specification in the presence of two subscribing witnesses.

MICHL. JOSEPH HOLLAND.
